PAPER PUNCH

William H. Misson, Los Altos, Calif.

Application April 6, 1948, Serial No. 19,269

2 Claims. (Cl. 164—91)

1

My invention relates to means for cutting a plurality of holes in one or more sheets of paper or the like and is especially concerned with a manually operated machine convenient for use in domestic or office surroundings.

It is an object of my invention in general to improve paper punches.

Another object of my invention is to provide a paper punch in which the work or manual force necessary to cut a hole in a single sheet or several sheets of paper is minimized.

Another object of the invention is to provide a paper punch in which centralized holes can be punched in sheets of different widths.

Another object of the invention is to provide a paper punch which is easy to manufacture, to assemble and to disassemble.

Other objects together with the foregoing are attained in the embodiment of the invention, described in the following description and illustrated in the accompanying drawings in which:

Figure 1 is an isometric view of my paper punch.

Figure 2 is a bottom view of the paper punch, a part of the bottom cover plate being removed to disclose the interior construction.

Figure 3 is a cross section, the planes of which are indicated by the lines 3—3 of Figure 2.

Figure 4 is a cross section, the planes of which are indicated by the lines 4—4 and 5—5 of Figure 3.

In its preferred form, the paper punch of my invention includes a base of hollow construction having a removable cover thereon and adapted to receive cutout portions of punched paper and being equipped with a detent centralized adjustable spacing guide for coordinating a sheet to be punched with a pair of reentrantly cut plungers slidably mounted in the base to descend through a paper slot. The plungers are propelled simultaneously by a spring returned handle pivotally associated with the base by yieldable strap supports, and having a stroke limiting bumper incorporated therein.

While the paper punch of my invention is susceptible to many different uses and varies in design somewhat depending upon its particular use and environment in which it is to be employed, it has been successfully fabricated in the form disclosed in the accompanying drawings. In this embodiment of the device there is provided a base member 6 which for quantity production purposes is preferably a metallic die-casting having a generally sloping top table 7 merging with a pair of side walls 8 and 9 as well

2

as with a small front wall 11 and a substantial rear wall 12. Between the inclined table 7 and the rear wall 12 there is a parallel top wall 13 spaced from the bottom of the structure to provide an interior compartment 14.

The bottom of the compartment is normally closed and a support is provided for the entire structure by a bottom cover plate 16, for example stamped of sheet metal and embossed to provide surface engaging feet 17 preferably elongated so that their shape makes them suitable to serve not only as supporting protuberances but likewise as reinforcing ribs. The closure plate 16 fits snugly within a marginal groove 18 cast into the body 6 and preferably is externally faced with flock or other suitable soft surface finish so that the punch when positioned on a smooth surface will not mar it.

In order that punchings can readily be removed from the compartment 14 without the necessity of detaching the plate 16 which is normally held in place by a plurality of screws 19 engaging bosses 21 formed integrally with the base 6, I provide a readily removable metallic plug 22. This is generally circular in contour and has a plurality of springy fingers 23 upstanding from it and designed to engage frictionally with the margin of an aperture 24 piercing the bottom plate 16. The plug readily may be removed by an operator and can as easily be forced back into position when the contents of the compartment 14 have been removed.

Since it is desired accurately to position a sheet or a plurality of sheets of paper or other material to be punched with respect to the base 6 and especially with respect to the inclined table 7, I provide a gauge means. This preferably comprises a strip 26 of metal or the like preferably diecast and of generally rectangular cross section having an upturned stop 27 at one end thereof. The slide 26 passes through apertures 28 and 29 in the side walls 8 and 9 respectively. In passing through the compartment 14 it is guided within a channel 31 formed by diecast portions of the table 7 depending into the compartment 14 and closed by an overlaid diecast housing 32. The housing is preferably formed with a plurality of apertures through which project pins 33 that are riveted or staked to form a final assembly.

The cover plate 32 near its center is cast with a depending boss 34 in which is disposed a detent mechanism. This comprises a spring 36 pressing against a ball 37 engaging any one of a number of depressions 38 formed at appropriate in-

ternals along the length of the slide 26. The depressions in the slide correspond in position with indicia such as numerals 39 cast on the slide to represent width divisions, for example inches of width of a sheet of paper. The indicia are made visible for adjustment of the slide through a window 41 centrally disposed in the inclined table 7 and provided with an arrow point 42 to indicate the centralization of the numeral.

Since the spacing of the numerals is preferably at half scale, the slide 26 can be moved so that if the width of a sheet of paper is known, its corresponding number when visible through the window 41 will indicate that the side stop 27 is in a position so that when the edge of the sheet is in contact with it, the sheet is centralized on the table. The provision of the spring thrust ball detent mechanism makes it simple to adjust the slide into designated or desired position yet holds the slide in such position against accidental dislodgement. For shipping purposes, or packing, the slide can readily be withdrawn from the apertures 28 and 29 so that the width of the structure is reduced. To prevent the ball 37 leaving its socket under those circumstances it is slightly staked in place.

In order that a sheet positioned upon the table 7 and especially upon the parallel surface 13 can be appropriately punched, I provide as a part of the base structure 6 a superstructure 44. For convenience in fabrication this is preferably a separate die casting and includes a rear wall 46, a top wall 47, and a pair of side walls 48 and 49 joined by a front wall 51 conveniently carrying a central index 52 in the nature of a projection in alignment with the projection 42. The superstructure 44 is held in position on the base 6 by a number of die cast projections 53 extending through apertures in the base and riveted or staked in position.

Projecting forwardly from the front wall 51 yet terminating at a distance above the table 13 are bosses 54 and 56 respectively which are substantially identical in construction so that a description of one applies equally to the other. Within the boss 54 is a sleeve 57 having a reduced circular cylindrical lower portion serving as a guide for a plunger 58 and having an enlarged upper portion serving as a housing for a spring 59 which encompasses the plunger and at its lower end rests against an offset in the sleeve. The lower end of the plunger 58 is provided with a re-entrant portion 61 in one view having an inverted V-shape and providing sharp edges of a symmetrical nature. The punch plunger 58 is designed to span the paper receiving aperture 62 between the bosses 54 and 56 and the upper surface 13 and to enter into a hardened ferrule 63 mounted in the base 6. When a piece of paper is disposed within the slot 62 overlying the ferrule 63 and the plunger 58 descends, the sharpened edges of the reentrant portion 61 pierce the paper uniformly from opposite sides so that there is no tendency to displace the paper or to displace the plunger 58. This provides an even cut and since the bottom of the V-shaped portion acts as a shear against the interior of the ferrule 63 a circular disc is severed cleanly from the paper sheet.

In order to operate both of the plungers 58 simultaneously there is provided an operating handle 64. This handle is preferably a die casting of generally rectangular shape and is provided adjacent each of its substantially identical sides with a rib 66. With the outside edge of the han-

dle, the rib provides material to receive a cross channel 67 in which is rotatably disposed a pin 68 piercing the plunger 58. The lips of the material defining the channel are slightly staked to overlie the pin 68 during assembly so that a substantially permanent connection is made. The contour of the material adjacent the side edge and the rib 66 is such as to afford an appropriate seat for the upper end of the coil spring 59, which therefore tends to raise or lift the handle 64 with respect to the base 6.

In order to serve as an appropriate fulcrum or pivot point for the punch yet in order to permit the plungers 58 to be translated without substantial side thrust or lateral force, I provide a yielding mounting. In the handle 64 at opposite sides thereof and spanning the space between the interior rib 66 and the outer wall, are aligned transverse pins 71 and 72. The pins are identical so that a description of one applies equally to the other. Each pin extends in from the outer surface and is readily removable although it is longitudinally fluted near one end and also is a tight enough frictional fit so that it does not rotate in the handle nor of its own accord become dislodged. The pin passes through an upper loop 73 formed in a metallic strap 74 of doubled material passing through an aperture 76 in the upper surface 47 of the superstructure. At its lower end the strap is extended to underlie the lower end of the ferrule 63 to serve as a deflector for severed paper discs and is bent to underlie the riveted head 77 of a projection passing through aligned apertures in the strap and forming part of the base 6. Since the material of the strap 73 is flexible and since the aperture 76 does not confine the strap, the motion of the handle 64 is primarily a rectilinear motion so far as the cross pins 68 are concerned and is slightly arcuate so far as the cross pins 71 and 72 are concerned. The result of this is to provide an easy and smooth motion for the handle and for the plungers 58.

To restrain the amount of action produced by the springs 59 and to serve as a stop, the handle 64 in its rearward portion is provided with a resilient bumper 78 designed to abut the top surface 47 of the superstructure with a cushioning effect so that the return motion of the punch is quietly arrested.

The structure is readily disassembled by withdrawal of the pins 71 and 72 from the loops 73 whereupon the plungers 58 and the handle are withdrawn from the superstructure, the springs 59 can be removed from the plunger, and the entire mechanism then inspected and by a reverse process re-assembled into operating condition.

In use, a sheet of paper is disposed upon the inclined table 7 with one edge of the sheet abutting the previously properly adjusted slide 26. When the forward edge of the paper has traveled up the incline 7 into the slot 62 and has come into abutment with the rear face of the slot, the operator depresses the handle 64. This simultaneously compresses the springs 59 and drives the plungers 58 downwardly through the paper and into the ferrules 63. The resulting punched out paper discs fall into the interior compartment 14 from which they can be subsequently removed. Upon release of the handle 64 the springs 59 restore it to its inactive position with the bumper 78 in abutment with the surface 37 and with the plungers 58 withdrawn from the slot 62 so that the appropriately perforated paper 75 can be removed.

I claim:

1. A paper punch comprising a base, a superstructure on said base and therewith providing a paper slot, said superstructure having apertures therein, a pair of plungers, means on said superstructure for guiding said plungers in a straight path to move across said slot, a lever for actuating said plungers, pins for pivoting said lever on said plungers, transversely spaced fulcrum pins on said lever, and wide metal flexible straps looped over said fulcrum pins passing through said apertures and secured to said base for flexibly fulcrumming said lever on said base.

2. A paper punch comprising a base inclusive of an interior compartment and having a top wall with openings and with plunger ferrules therein; a separate superstructure abutting said base and overlying part of said top wall to provide a paper receiving aperture therebetween, said superstructure having openings in line with said openings in said top wall; plungers reciprocable in said superstructure for movement into said ferrules; means for interconnecting said superstructure and said base; a lever pivoted on said plungers; transversely spaced fulcrum pins on said lever; wide metal flexible straps looped

5

over said fulcrum pins, passing through said openings in said superstructure and through said openings in said top wall; and fasteners in said compartment for securing said straps to said base.
